MONROE S. HOWARD, OF WAUKON, IOWA.

AUTOMATIC EXPRESSION CONTROL FOR PLAYER-PIANOS.

1,190,172.

Specification of Letters Patent.

Patented July 4, 1916.

Application filed June 22, 1915. Serial No. 35,572.

To all whom it may concern:

Be it known that I, MONROE S. HOWARD, a citizen of the United States, and a resident of Waukon, in the county of Allamakee and State of Iowa, have invented an Improvement in Automatic Expression Control for Player-Pianos, of which the following is a specification.

One of the principal objects of this invention is to provide an improved means for varying the force with which the individual notes of the piano are struck, and thus embodying to the maximum degree the accent, touch and expression, and the varying degrees of loudness utilized by a pianist in giving expression to a composition, by directly regulating the degree of vacuum attained in the individual striking pneumatics of the player mechanism.

Another object is to provide means for directly regulating the degree of vacuum in the striking pneumatics through the arrangement, disposition, and formation of the openings cut in the music roll, so that an artist's rendition of a musical composition may be exactly reproduced by the use of a music roll cut according to a record made by the pianist during the rendition of the composition.

A further object is to provide a control for the individual striking pneumatics, by connecting them with the tracker bar of the apparatus and by controlling the admission of air at atmospheric pressure to the striking pneumatics through the action of the music roll in controlling the auxiliary openings provided in the tracker bar and which are in communication with the striking pneumatics, so that the degree of vacuum obtained in these pneumatics may thus be regulated and hence the force of the strokes given the notes through the action of the pneumatics be automatically varied and controlled.

A still further object is to provide a device of the class described which will be extremely simple, durable, efficient in operation and inexpensive to manufacture.

With these and other objects in view which will become apparent as the descrip-

tion proceeds, the invention resides in the construction, combination and arrangement of parts hereinafter more fully described and claimed, and illustrated in the accompanying drawings in which like reference characters indicate similar parts throughout the several figures, of which--

Figure 1 represents a view in section taken vertically and transversely through the operating mechanism of a player piano, embodying one conception of my invention. Fig. 2 represents a similar view showing a modified conception of the device. Fig. 3 represents a fragmentary elevational view of a tracker bar and music sheet.

My invention is capable of being used with many various kinds of operating mechanisms for player pianos, and is here shown as in use in a mechanism of well known construction. This operating mechanism includes the tracker bar 5 over which the perforated music sheet is drawn in controlling the operation of the mechanism as usual. The ordinary striking pneumatic through whose action the notes are struck is indicated at 6. Each of the notes of the piano is controlled by one of the pneumatics as usual. The exhaust chamber of the apparatus is indicated at 7, and is connected as usual with the striking pneumatic by means of the passage 8. The valve mechanisms through whose co-action the establishment of communication between the striking pneumatic 6 and the exhaust chamber 7 is attained, are indicated at 9 and 10. The usual communication between valve 9 and the tracker bar is established through the tube 11. The operation of the device in exhausting the air in the striking pneumatic to sound a note is well known in the art and therefore need not here be set out.

My invention relates to the manner in which the amount of vacuum created in the striking pneumatic is attained, in varying the force of the blows struck by the pneumatic. In connection with each of the arrangements of the device indicated in Figs. 1 and 2, and indeed with other arrangements which may fall within the scope of this invention, I utilize a tracker bar having

auxiliary openings 12 alternating with the usual openings 13 provided in the tracker bar and through the uncovering of which latter openings, by registration therewith of the perforations of the music sheet the operation of the mechanism in striking the various notes is attained. These auxiliary openings 12 are arranged preferably transversely of the tracker bar and alternately with openings 13 as shown, and are preferably of a uniform length and width.

In the embodiment indicated in Fig. 1 a chamber 14 is provided which communicates directly with the striking pneumatic 6, through a passage 15. Arranged in this chamber is a valve 16 adapted to be controlled by a pneumatic 17. The valve is adapted to control an opening 18 provided in the upper wall of the chamber and through which opening communication to the outside atmosphere may be established. Valve 16 is preferably in the form of an inverted cone and the edges defining the opening 18 are preferably beveled, so that as the valve is raised the size of the opening may be enlarged in order that the quantity of air thus admitted to chamber 14 when valve 16 is raised, may be controlled. The valve is maintained in closed position partially through the action of a leaf spring 19 carried by the chamber 14 on the outside thereof and controllable by a set screw 20 whereby the tension of the spring may be varied. A tube 21, communicating at its outer end with one of the auxiliary openings 12 in the tracker bar, is in communication at its inner end with the valve controlled pneumatic 17, through the medium of a passage 22. This passage is in communication with the exhaust chamber 7 through the medium of a bleed tube 23.

The pressure of the air in tube 21, passage 22 and pneumatic 17 may through the medium of the tube 23 be reduced to the same tension as the air in the exhaust chamber 7. Normally the air in the parts mentioned is exhausted to the same pressure as that in the exhaust chamber when the auxiliary opening is covered by the solid portion of the music sheet. This sheet as indicated in Fig. 3 is provided with perforations or openings 24, portions of which, as at 25, are in alignment with and adapted to pass over the various striking pneumatic control openings 13, while other portions 26 thereof are in alignment with and adapted to pass over the auxiliary openings 12. If a note is struck by uncovering one of the openings 13 without uncovering its auxiliary opening 13, there is no tendency for the valve 16 to rise, because tube 21, passage 22 and pneumatic 17 are exhausted to the same pressure as that attained in the exhaust chamber 7, and hence the striking

pneumatic 6 will be collapsed with a maximum force and hence the force exerted in striking the note will not be diminished. If, however, the auxiliary opening 12 is more or less uncovered by the opening in the music sheet the partial vacuum in the pneumatic 17 tending to keep the same collapsed, will be relieved by an amount depending upon the amount of atmospheric air admitted through the auxiliary opening. If the striking pneumatic actuating mechanism is then put into operation, as soon as the pressure in the striking pneumatic 6 and chamber 14 falls below that in the pneumatic 17, sufficiently, the resistance of the spring 19 and the pressure of atmospheric air on the valve 16 will be overcome and this valve will be allowed to open, and thus atmospheric air will be admitted to the chamber 14 and to the striking pneumatic 6 so that further reduction of the pressure in the pneumatic will be prevented and the pneumatic will thus be prevented from striking a blow with full force. It follows that the force of the blow struck by the pneumatic 6 may be varied, and substantially any degree of force attained by controlling the amount of air admitted through the auxiliary opening.

In the modification shown in Fig. 2 the chamber 14, valve 16, pneumatic 17 and bleed tube 23 are dispensed with, and the tube 21 is connected directly with the interior of the striking pneumatic 6 through the medium of the passage 15'. The operation in this case is substantially similar to the operation previously described, except that in the form shown in Fig. 2 the atmospheric air is admitted directly into the pneumatic 6 through the auxiliary opening 12, the amount of air so admitted being controlled by the amount of the opening uncovered by the perforation of the music roll. Both of the devices shown will obtain the same result, namely, that of controlling the amount of vacuum created in the striking pneumatic 6 by admitting a greater or less amount of atmospheric air to the striking pneumatic. However, the device shown in Fig. 1 is of a more sensitive nature than that shown in Fig. 2.

By varying the shape of the advance or forward ends of the openings 24 provided in the music sheet, the action of the various striking pneumatics, and hence the force of the blows by which the notes are struck may be regulated.

It will of course be understood that each individual striking pneumatic is provided with the mechanism whereby the amount of vacuum created in the striking pneumatic may be regulated, so that the force with which each note is struck may thus be controlled. The openings or perforations pro-

vided in the music sheet thus have the same control over the force with which the individual notes are struck, as is exercised by a pianist in playing an instrument manually. By the use of my invention a music sheet perforated according to a record made by a pianist in rendering a selection, may be used to control the operation of the striking pneumatics in such manner as to exactly 10 imitate the varying degrees of loudness, accent, touch and expression employed by the artist, and thus his conception and individuality may be effectively reproduced.

Although I have described the preferred 15 embodiment of my invention, I may desire to make such changes in the construction, combination and arrangement of parts thereof, as do not depart from the spirit of the invention and the scope of the appended 20 claims.

I claim:—

1. In an automatic player piano including a tracker bar and a striking pneumatic, and means between the tracker bar and striking 25 pneumatic for actuating the latter, said means including an exhaust chamber, the combination of a chamber communicating directly with the striking pneumatic, and being provided with a valve for admitting air 30 at atmospheric pressure to the chamber when opened, a control pneumatic for the valve, a passage connecting said valve control pneumatic with an opening in the tracker bar, whereby air at atmospheric pressure may be 35 admitted to said valve control pneumatic when the auxiliary opening is uncovered, a bleed tube connecting said passage with said 40 exhaust chamber whereby the pressure of air within the passage may be reduced to the pressure of air within the exhaust chamber when said opening is closed, and a music sheet provided with perforations adapted to 45 be brought into registration with said opening for uncovering it to various degrees whereby the amount of atmospheric air admitted to the said passage may be controlled.

2. In a player piano including a tracker bar and a striking pneumatic and means connecting them whereby the striking pneumatic 50 may be actuated for striking a note, said means including an exhaust chamber, the combination of a chamber communicating directly with the striking pneumatic and being provided with a valve adapted when 55 opened to allow atmospheric air to enter said chamber whereby to pass into the striking pneumatic, a control pneumatic for controlling the action of said valve, a passage connecting said control pneumatic with an 60 opening in the tracker bar, a bleed tube connecting said passage and the said exhaust chamber, and means whereby the auxiliary opening may be uncovered and covered to various degrees.

3. In a player piano, the combination of a 65 tracker bar, a striking pneumatic, means connecting the tracker bar and striking pneumatic whereby the latter may be actuated for striking a note, a valve control means operably connected with said striking 70 pneumatic whereby atmospheric air may be admitted to the striking pneumatic when the valve is opened, a pneumatic for controlling the valve, a passage connecting the pneumatic with an opening in the tracker bar, and 75 means whereby the pressure within the passage may be reduced when the opening is covered whereby to maintain the valve in closed position, and a music sheet arranged across the opening and being provided with 80 a plurality of perforations adapted to uncover said opening to various degrees as the music sheet passes thereover.

4. A player piano including a tracker bar, a striking pneumatic, means connecting the 85 tracker bar and striking pneumatic whereby the latter may be actuated for sounding a note, means communicating with the striking pneumatic and with an opening provided in the tracker bar, whereby air at at- 90mospheric pressure may be admitted to the striker pneumatic when the opening is uncovered, and a music sheet adapted to be drawn across said tracker bar for normally covering the opening, said music sheet being 95 provided with a plurality of apertures adapted to be brought into registration with said opening for uncovering the latter to various degrees whereby various amounts of atmospheric air may be admitted to the 100 striking pneumatic.

5. A player piano including a tracker bar and a striking pneumatic, and means communicating with the tracker bar and striking pneumatic whereby atmospheric air may 105 be admitted to the latter for reducing the force of the blow struck by the striking pneumatic.

6. In a player piano, the combination with a tracker bar and striking pneumatic, of 110 communicating means between the tracker bar and striking pneumatic whereby air at atmospheric pressure may be admitted to the latter for lessening the blow of the striking pneumatic and means whereby the amounts 115 of atmospheric air so admitted may be controlled.

7. A player piano including a tracker bar and a striking pneumatic, and means whereby atmospheric air may be admitted to the 120 latter as it collapses for modifying the stroke of the pneumatic.

8. A player piano including a tracker bar provided with an opening, a striking pneumatic, means connecting the tracker bar and 125 striking pneumatic whereby the latter may be actuated for striking a note, communicating means between the opening and the

striking pneumatic whereby air may be admitted to the latter when the opening is uncovered, and means whereby the opening may be uncovered to various degrees for determining the amount of air admitted to the striking pneumatic.

9. In a player piano, the combination of a

striking pneumatic, means for normally exhausting the pneumatic for collapsing the same with maximum force, and means for admitting atmospheric air to the pneumatic at will during its collapsing movement for modifying the force of the stroke.

MONROE S. HOWARD.
